OF CLEVELAND, OHIO

ELECTRICAL STARTING SYSTEM FOR INTERNAL COMBUSTION ENGINES

Application filed September 12, 1929. Serial No. 392,153.

This invention pertains to an electrical starting system for internal combustion engines, and is an improvement especially applicable to automobiles or other motor driven vehicles in which an electric starting motor, storage battery, and generator, are used. The engine may include a power transmitting clutch controlled by a foot pedal as usual; an electric starting motor geared to the engine by such known means as the so-called Bendix drive; and also an electric generator driven by the engine having a cut-out relay adapted to keep the storage battery in a charged condition for starting, ignition, and lighting purposes. My object in general, is to utilize such known devices in circuit with an electro-magnetic switch, substantially as herein-after described, whereby the engine may be started, preferably by manipulating the clutch pedal, and then when the engine is operating under its own power, using the pressure or voltage of the generator to energize the electro-magnetic switch to stop the starting motor. In a preferred form of the invention, an electro-magnetic switch is used to make and break the battery circuit for the starting motor, and the clutch pedal is utilized to make and break a controlling circuit which includes the coil of the electro-magnetic switch and also the generator windings. In operation, when the operator of the vehicle depresses the clutch pedal and throws out the engine clutch, the controlling circuit is closed and the electro-magnetic switch is energized, thereby starting the engine by closing the starting motor circuit. The voltage of the generator depends upon the speed at which the engine is driven, all other factors remaining constant, and at low engine speed the voltage is not high enough to charge the battery or to affect the electro-magnetic switch adversely. However, when starting of the engine has been accomplished, the speed of the engine increases and at a given speed the voltage of the generator equals the electromotive force of the battery. Under that condition the electro-magnetic switch will be deprived of its force and caused to open, thereby breaking the circuit for the starting motor and stopping the same. Also, as long as the engine and generator are running normally, the electro-magnetic switch will be rendered feeble or impotent, and the starting motor cannot be operated, should the pedal be depressed to its full extent and the pedal switch closed. However, should the engine stall and stop, the original conditions will be resumed, and the engine can be started again in the way described.

In the accompanying drawings, Fig. 1 is a sectional view of a portion of an automobile, showing an internal combustion engine and an electrical starting system therefor constructed and arranged according to my invention, and Fig. 2 is a diagram of the electric circuits and parts therein. As thus delineated the invention includes an internal combustion engine E, having an electric starting motor M, and an electric generator G operatively geared thereto as customarily. The transmission of power from the engine to the driven member involves as usual a friction clutch (not shown); also a foot pedal P, for throwing the clutch members into and out of engagement. The starting motor M, and generator G, are electrically connected to a storage battery B, and to a manually operable switch S on the instrument board I. Switch S controls an ignition circuit 2 for engine E, and also a second circuit 3 connecting the coil or winding 4 of an electro-magnetic switch A, with a pedal operated switch P', and the windings of generator G, including the windings 5 of the cut-out relay R which is ordinarily associated with or forms a part of the generator. Thus, magnet coil 4, and pedal switch P' are connected in series with the windings of generator G and relay coil 5, and circuit 3 may be closed and opened by foot pedal P, at the election of the operator. When ignition switch S is closed, and circuit 3 is also closed by pedal switch P', the electro-magnetic switch A is energized, assuming engine E is not running under its own power. The closing of pedal switch P' closes motor circuit 6 and starts motor M and engine E, thereby also starting generator G. Ordinarily, when engine E starts and comes up to speed, the gearing for the starting motor is automatically discon-

5 nected, using the customary self-releasing starting mechanisms. The operator may still continue to press pedal P and hold switch P' closed, inasmuch as provision is made to use the voltage of generator G to render coil 4 inactive and open the electro-magnetic switch A, thus cutting off the battery current from motor M.

10 The principal function of generator G is to keep storage battery B in a charged condition. In charging the battery the current must flow in a reverse direction to that in discharging. To accomplish this, the voltage of the generator must be somewhat higher than the back pressure or electromotive force of the battery. In starting or at low engine speed, the voltage is not high enough to charge the battery. When the engine is stopped entirely, the voltage of the generator falls to zero, due to the low resistance of the armature of the generator, and the battery can be caused to discharge through circuit 3 and the generator windings. For that reason the electro-magnetic switch coil 4 is connected in series with the generator so that it may be energized by the battery current in starting operations. To prevent discharge of the battery when the engine is not running nor being started, the cut-out relay R 30 is inserted into the charging line 7 between the generator and the battery.

Thus, the main function of cut-out relay R is to automatically close a charging circuit 7 between the generator and battery when the pressure of the generator is slightly in excess of the back pressure or electromotive force of the battery. When the pressure of the generator drops slightly below that of the battery (due to low engine speed), 40 the switch or cut-out relay automatically opens charging circuit 7, thus preventing the battery from discharging back through this circuit and the generator windings.

When the engine is running under its own power, no mal-function or ill effect will arise should the operator depress pedal P and close switch P', irrespective of the speed of generator G. Thus if the generator is running at a speed sufficient to charge the battery the relay R will be closed, thus providing a direct path over circuit 7 to the battery for the generator current. Practically no generator current will then flow back to the battery through circuit 3, due to the resistance of electro-magnetic coil 4. On the other hand if the generator voltage is not sufficient to charge the battery, voltage is created nevertheless in opposition to that of the battery with such neutralizing effect that electro-magnetic switch A will not close but will be held open by the tension of a spring 8. Starting can be effected when the engine is entirely stopped or stalled by simply depressing the clutch pedal P which causes the 60 battery current to close the single electro-

70 magnetic switch A. Then, as the generator G and cut-out relay R are in the same circuit as this electro-magnetic switch they in themselves prevent the starting motor from being operated when the engine is running at idling or higher speeds.

Pedal P may be operated to throw out the clutch without actuating switch P', and to achieve that purpose switch P' is preferably mounted apart from pedal P where it will 75 only be engaged and operated by the pedal at the end of its throw-out stroke and when moving idly. However, the switch P' may be operated in any other suitable way; or it may be omitted.

If switch P' is omitted, and control of circuit 3 is effected solely by the ignition switch S, I prefer to use an ignition switch embodying two separate contacts 8 and 9, respectively, for the ignition circuit 2 and the controlling circuit 3, substantially as delineated in Fig. 2. In that case when ignition switch S is opened a break is effected between the ignition circuit 2 and the controlling circuit 3, and generator G is cut off entirely from the ignition circuit. Otherwise under certain conditions the engine would continue to run on the generator current flowing over circuits 3 and 2, assuming pedal switch P' to be closed or omitted. Preferably a pedal controlled switch is used, as an inexperienced or careless operator cannot start the engine without throwing out the clutch or with the gears in mesh. Should the motor stall or stop in traffic, or on a hill or up-grade, 100 starting can be effected by disengaging the clutch with one foot while controlling the brake with the other foot and operating the throttle controls on the steering wheel by hand.

105 What I claim, is:

1. In an electrical starting and ignition system for internal combustion engines, an engine having an electric starting motor and an ignition circuit and electric generator operatively connected therewith; a cut-out relay for said generator in a charging circuit for said battery; a storage battery and a circuit therefor, including said starting motor and a starting and stopping switch; and a controlling circuit for said switch connecting said battery and generator, including a magnetic controlling device for said switch and a manually operable switch for controlling said ignition circuit and said controlling circuit; said manually operable switch including means for completely disconnecting said controlling and ignition circuit and for causing a complete break therein, said manually operable switch having a contact associated with said controlling circuit and a contact associated with said ignition circuit, said magnetic controlling device being adapted to be energized when the engine is idle and ren- 110 115 120 125 130

dered impotent by the voltage of the generator when the engine is running.

2. In a system substantially as herein described, an internal combustion engine having an electric generator, and an electric starting motor operatively connected therewith, the generator having a battery cut-out relay; a storage battery electrically connected in a charging circuit with said generator and relay; an ignition circuit for said engine; a starting circuit having a main switch to control starting and stopping of said electric motor; and a controlling circuit, including an electro-magnet and winding for operating said main switch, the generator and relay windings, said battery, and a manually operable double contact, single blade switch for electrically connecting said ignition and controlling circuits with the battery and capable of completely breaking the ignition and controlling circuits in respect to each other as well as completely breaking each respective circuit to prevent feed back of the generator current to the ignition circuit when the battery current is cut off by said switch.

3. In an electrical starting and ignition system, an internal combustion engine, an ignition circuit, a battery therefor, an electrically operable starting motor and an electrically operable generator operatively connected therewith, a cutout relay for said generator in a charging circuit to said battery a circuit including said starting motor and an electromagnetic switch subjected to energization by said battery, a controlling circuit for said magnetic switch including a manually operable double contact switch, one of said contacts being placed in the ignition circuit and the other of said contacts being placed in said controlling circuit, said ignition and controlling circuit being electrically connected when said switch is closed and each circuit respectively being completely broken and separated each from the other when said switch is open.

In testimony whereof I affix my signature.
HENRY D. STECHER.
